UNITED STATES PATENT OFFICE

ROBERT D. BUDLONG, OF CHICAGO, ILLINOIS, ASSIGNOR TO THE HAMMOND CLOCK COMPANY, OF CHICAGO, ILLINOIS, A CORPORATION OF DELAWARE

DESIGN FOR A COMBINED DIAL AND HANDS FOR A CLOCK

Application filed June 29, 1931. Serial No. 40,360. Term of patent 14 years.

To all whom it may concern:

Be it known that I, ROBERT D. BUDLONG, a citizen of the United States, and resident of Chicago, in the county of Cook and State of Illinois, have invented a new, original, and ornamental Design for Combined Dial and Hands for a Clock, of which the following is a specification, reference being had to the accompanying drawing, forming a part thereof.

The figure is a plan view of a combined dial and hands for a clock, showing my new design.

I claim:

The ornamental design for a combined dial and hands for a clock, as shown.

In witness whereof, I hereunto subscribe my name this 25th day of June, 1931.

ROBERT D. BUDLONG.
